[57] ABSTRACT

Solid granular fertilizers based on the inclusion of phosphoric acid as an additive to urea and consisting of a homogeneous mixture of two solid crystalline phases, i.e., urea and urea phosphate, and ranging in its overall N:P₂O₅ weight ratio from about 2:1 to about 5:1, preferably from about 2:1 to 3:1. These fertilizers are suitable for surface application, especially where immediate

incorporation into the soil is not practicable, such as on pastures, or undesirable such as in conjunction with reduced tillage practices, and generally wherever it is necessary or desirable to apply nitrogen on the surface of soil, ensuring substantially reduced losses of urea nitrogen by volatilization, and causing a delay of 4 to 7 days in the commencement of such losses. The product is also suitable for band application, resulting in eliminating the problems of seedling damage and crop stand reduction which are associated with urea or combinations of urea and ammonium phosphates, particularly diammonium phosphate.
